UNITED STATES PATENT OFFICE.

EDMUND F. HARTSHORN, OF NEWARK, NEW JERSEY, ASSIGNOR TO STEWART HARTSHORN COMPANY, OF EAST NEWARK, NEW JERSEY, A CORPORATION OF NEW JERSEY.

SPEAR FOR SPRING SHADE-ROLLERS.

1,093,930.

Specification of Letters Patent. Patented Apr. 21, 1914.

Application filed July 1, 1912. Serial No. 706,879.

To all whom it may concern:

Be it known that I, EDMUND F. HARTSHORN, a citizen of the United States, residing in Newark, county of Essex, State of 5 New Jersey, have invented a certain new and useful Spear for Spring Shade-Rollers, of which the following is a specification.

The object I have in view is the production of a spear for use in connection with 10 spring shade rollers.

The particular objects are to simplify the spear, reduce the cost thereof, and render it more easily attached to the spindle.

These and further objects will more fully 15 appear from the following specification and the accompanying drawings, considered together or separately.

The invention may be considered as an improvement on the spear disclosed in my 20 co-pending applications for patent, both filed June 25, 1910, Serial Nos. 568,763 and 568,764.

In the accompanying drawings, Figure 1 is a side elevation of a spear embodying my 25 invention, in connection with a spring shade roller, certain parts of the roller being shown in section. Fig. 2 is an end view of the roller illustrated in Fig. 1. Fig. 3 is a perspective view of a spear embodying the 30 invention, shown in connection with the end of the spindle to which it is to be attached.

In all of the views, like parts are designated by the same reference characters.

Referring to the drawings, the spear 1 is 35 shown of general flat cross-sectional shape. I prefer to make it of steel or other suitable material. It may be a casting, stamping, or made in any other manner. The spear 40 comprises a body 2, with a tip 3 extending from one end. This tip is sufficiently long to serve three functions: the part nearest the body serves as a bearing in the cap; the part intermediate the ends serves as a 45 ratchet for engagement with the pawls; and the part at the extreme end serves as a support for engagement with the usual supporting bracket. I prefer to make the tip of rectangular section, as shown. I also 50 prefer to make it of the same dimensions throughout its length, and of the same cross-sectional shape in all parts. This makes a very simple fitting, with a minimum amount of work upon it. The spear 55 is adapted to be attached to the spindle in

any suitable manner. The means illustrated comprise two legs 4, 4. They extend out from the body 2, in the opposite direction from the tip 3. These legs are adapted to straddle the ends of the spindle in the manner to be described. I prefer to make the tip 3 of less width than the body 2. This will produce shoulders 5, 5, between the body and tip. These shoulders are adapted to engage with the inner side of the cap to be 60 described, and, therefore, prevent the spindle from moving longitudinally in the direction toward the cap. 65

I prefer to bevel the ends of the inner edges of the legs at 6, as shown. This, however, is not necessary. By beveling the legs the end of the spindle is more easily inserted between them. I also prefer to round the outer edges of the legs at 7. A spring (to be described) surrounds the legs, and by 70 rounding the outer edges of the legs, the wear upon the spring when it comes in contact with the legs is reduced. 75

This improved spear is adapted to be used with a spindle, such as 8. In order to attach the spear to the spindle, the latter is provided, at one end, with oppositely disposed grooves 9, 9. These grooves are sufficiently long to form beds for the legs when the latter straddle the end of the spear. 80 The depth of the grooves and their width will be such that the legs of the spear will produce a tight fit when the spear is driven in place, and will so be retained. The end of the spindle is preferably provided with a 85 notch 10, at right angles to the before-described grooves. This notch receives the end of the spring 11. The spear being seated upon the end of the spindle, will retain the end of the spring within the notch. 90 The usual roller 12 is adapted to contain the spear, spindle and spring. The end of the roller is inclosed by a ferrule 13, of the usual shape. This ferrule retains the cap 14 in position. The cap 14 is of the usual shape, 100 and is provided with a central opening, which forms a bearing for the spear. The cap also carries the pawls 15, 15. Any form of pawl may be used, but those illustrated are preferred. Each pawl is provided with 105 a notch 16. This notch is angular in shape, and is adapted to engage with the square end of the tip.

The parts are assembled as shown in Figs. 1 and 2. The shoulders 5, 5, abut against 110

- the inner side of the cap. The opening is larger than the tip, but smaller than the shoulders, so that the shoulders engage with the cap. It will be seen that the tip serves 5 three functions, already described. It engages within the bearing in the cap; it serves as a ratchet for engagement with the pawls; and its projecting extremity serves as a support for engagement with the bracket.
- 10 I have found that the squared edges of the tip mounted within the bearing in the cap form a satisfactory support for that end of the roller. I find that there is no need of rounding the edges of the tip for the engagement of the bearing. I also find that the pawls readily engage with the squared edges of the tip and lock the roller against 15 rotation. According to my invention, I produce a very satisfactory spear of the 20 simplest shape.
- In accordance with the provisions of the patent statutes, I have described the principle of my invention, together with the apparatus which I now consider to represent 25 the best embodiment thereof; but I desire to have it understood that the apparatus shown is merely illustrative and that the invention can be carried out in other ways.
- Having now described my invention, what 30 I claim as new and desire to secure by Letters Patent, is:
1. A spear for a spring shade roller, of substantially rectangular cross - section throughout its length and having a long flat tip of the same cross-section throughout, said tip being adapted for engagement with the pawls, and also with the supporting bracket.
  2. A spear for a spring shade roller, of substantially rectangular cross - section 40 throughout its length, with a long flat tip, of the same cross-section throughout, said tip being adapted for engagement with the pawls and also with the supporting bracket, and means for engaging the spear with the 45 spindle.
  3. A spear for a spring shade roller, of substantially rectangular cross - section throughout its length with a tip, of the same cross-section throughout its length, said tip being sufficiently long to be engaged by the 50 pawls and also engaged by the supporting bracket.
  4. A spear for a spring shade roller, of substantially rectangular cross - section 55 throughout its length, with a portion adapted to engage with the spindle, also having a tip, said tip being of uniform cross-section throughout its length and having a portion which is adapted to engage with the pawls, 60 and a portion which is adapted to engage with the supporting bracket.
5. A spear for a spring shade roller, of substantially rectangular cross - section throughout its length and having a long flat tip of uniform cross-section throughout, 65 said tip being adapted for engagement with the pawls, and also with the supporting bracket, said spear having legs which straddle the spindle and engage with it.
6. A spear for a spring shade roller, 70 of substantially rectangular cross - section throughout its length and having a long flat tip, of uniform cross-section throughout, said spear having a body portion with shoulders, said tip being adapted for engagement 75 with the pawls and also with the supporting bracket, and said shoulders being adapted for engagement with the cap, and means for engaging the spear with the spindle.
7. A spear for a spring shade roller, 80 of substantially rectangular cross - section throughout its length and having a long flat tip of uniform cross-section throughout, said tip being adapted for engagement with the pawls, and also with the supporting 85 bracket, and having legs which straddle the spindle and engage with it, the inner edges of the legs being beveled.
8. A spear for a spring shade roller, 90 of substantially rectangular cross - section throughout its length and having a long flat tip of uniform cross-section throughout, said tip being adapted for engagement with the pawls, and also with the supporting 95 bracket, and having legs which straddle the spindle and engage with it, the outer edges of the legs being rounded.
9. In a spring shade roller, a spear of substantially rectangular cross-section throughout its length and having a long flat tip of 100 uniform cross-section throughout, said tip being adapted for engagement with the pawls, and also with the supporting bracket, in combination with pawls, said pawls having notches which engage with the squared 105 edges of the tip.
10. In a spring shade roller, a spear of substantially rectangular cross-section throughout its length and having a long flat tip, of uniform cross-section throughout, said tip being connected to the body by separating shoulders, in combination with a cap, said cap carrying pawls, the ends of the pawls being notched, which engage with the tip, and the shoulders engaging with the cap. 110
- This specification signed and witnessed 115 this 20th day of June, 1912.
